(57) **CLAIM**

The ornamental design for an “insulated plant container,” as shown and described.

DESCRIPTION

FIG. 1 is a perspective view of an “insulated plant container” showing my new design;

FIG. 2 is a top plan view thereof;

FIG. 3 is a bottom plan view thereof; and,

FIG. 4 is a cross-sectional view thereof, taken along lines 4-4 of FIG. 2 and shown at an enlarged scale.
